US00D876728S

(12) **United States Design Patent** (10) **Patent No.:** **US D876,728 S**
(45) **Date of Patent:** **** Feb. 25, 2020**

(54) **MOUTH GUARD**

(71) Applicant: **Battle-ABC, LLC.**, Omaha, NE (US)

(72) Inventors: **Michael Evans**, Elkhorn, NE (US);
Christopher W. Circo, Bennington, NE (US);
Jeffrey M. Evans, Omaha, NE (US)

(73) Assignee: **BATTLE-ABC, LLC.**, Grand Island, NE (US)

(**) Term: **15 Years**

(21) Appl. No.: **29/569,787**

(22) Filed: **Jun. 30, 2016**

Related U.S. Application Data

(63) Continuation-in-part of application No. 29/511,660, filed on Dec. 12, 2014, now Pat. No. Des. 760,889, which is a continuation-in-part of application No. 13/666,698, filed on Nov. 1, 2012, now Pat. No. 8,931,488.

(57) **CLAIM**

The ornamental design for a mouth guard, as shown and described.

DESCRIPTION

FIG. 1 is a front perspective view of the mouth guard; FIG. 2 is a rear perspective view of the mouth guard; FIG. 3 is a front elevation view of the mouth guard; FIG. 4 is a top plan view of the mouth guard; FIG. 5 is a rear elevation view of the mouth guard; FIG. 6 is a side elevation view of the mouth guard; and, FIG. 7 is a bottom plan view of the mouth guard. The broken lines in the drawings depict portions of the mouth guard that form no part of the claimed design.

1 Claim, 7 Drawing Sheets
